[57] ABSTRACT

A polyphase digital filterbank extracts a spectral envelope composed of thirty-two bands, having uniform bandwidths, from a speech signal. The spectral envelope is then compressed into a predetermined number of bands having uniform bandwidths. Spectral energy features are extracted from the compressed envelope and are utilized to form templates representing the speech signal.

**APPARATUS FOR EXTRACTING FEATURES
FROM A SPEECH SIGNAL**

**CROSS-REFERENCE TO RELATED
APPLICATIONS**

This application is related to one, or more, of the following U.S. patent applications: Ser. No. 659,989, U.S. Pat. No. 4,799,144 filed Oct. 12, 1984; Ser. No. 670,521 filed on Nov. 9, 1984. All of the above applications are assigned to the assignee hereof.

BACKGROUND OF THE INVENTION

The present invention generally relates to an apparatus for extracting features from a speech signal and, in particular, relates to one such apparatus that employs a polyphase digital filterbank for extracting a spectral envelope from a speech signal.

In the field of speech recognition and/or speaker verification as opposed to, for example, any revocalization of a spoken word, a relatively small number of features are required for the desired identification. However, in order to provide a reliable system, the extraction of those features must be accomplished accurately and consistently.

The accurate and consistent extraction of spectral features is, to a very large degree, dependent on a filterbank. That is, an analog speech signal representing a spoken word has an amplitude that changes with both frequency and time. Such a signal is sampled in both the time and frequency domains. The frequency domain samples, at each sampling time, contain the primary spectral features of interest. Thus, in order to extract such features, for each time sampled signal, the frequency domain signal is formed by filtering.

Until recently, filterbanks for speech recognition systems have been implemented using analog filter theory and technology. Analog filterbanks usually perform somewhat poorly. This poor performance is primarily due to the inherent limitations of analog components, i.e., analog components are inherently very difficult to reproduce with the accuracy necessary for speech recognition applications. In addition, the values of analog components inherently vary over time and are susceptible to such factors as temperature changes, surrounding radiation and the like. Thus, to provide an analog filterbank of acceptable quality, very precise, and correspondingly expensive, components must be used.

The relatively recent development of high speed digital signal processors has allowed the design and implementation of filterbanks based on digital filter theory and technology. The very nature of digital technology results in high performance digital filterbanks having exact response predictability. The performance of such digital filterbanks directly depends on the binary word length of the digital signal processor hardware used in the implementation thereof.

Nevertheless, it is not a straight forward task to design a high performance digital filterbank. For example, using a conventionally designed digital filter, a modern digital signal processor operating at full capacity and conventional techniques provides a filterbank having a dynamic range of about 45 dB and a 14 band spectral envelope. Since the human voice has a dynamic range about 45 dB, such performance characteristics are barely adequate for a reasonably accurate speech recognition/speaker verification system. That is, the above performance characteristics would require a user to

speak in a monotone to avoid loss of information. The number of bands extracted is directly related to the resolution of the filterbank. Thus, the more bands the greater the accuracy and consistency of the features extracted.

In addition to the general filterbank design difficulties, conventional speech recognition/speaker verification systems usually exhibit poor performance due to other difficulties. One difficulty results from the fact that filterbanks are composed of a set of nonoverlapping band pass filters, each having a finite transition band. Due to the somewhat periodic nature of a speech signal, the speech spectrum manifests a relatively strong fundamental pitch frequency. When this fundamental pitch frequency occurs between adjacent bands important spectral information is lost and the results become less accurate.

SUMMARY OF THE INVENTION

Accordingly, it is one object of the present invention to provide an apparatus for extracting features from a speech signal that exhibits an increased dynamic range.

This object is accomplished, at least in part, by an apparatus having a polyphase digital filterbank for extracting a spectral envelope from a speech signal such that the extracted spectral envelope is composed of a plurality of bands of the same bandwidth.

Other objects and advantages will become apparent to those skilled in the art from the following detailed description read in conjunction with the appended claims and the drawings attached hereto.

BRIEF DESCRIPTION OF THE DRAWINGS

FIG. 1 is a block diagram of an apparatus for extracting features from a speech signal;

FIG. 2 is an input spectrum of a sampled speech signal;

FIG. 3 is a composite frequency response of the polyphase digital filterbank shown in FIG. 1;

FIG. 4 is a block diagram of a basic polyphase digital filter;

FIG. 5 is a graphic representation of how a low pass filter is modulated to form a band pass filter;

FIG. 6 is a block diagram of a preferred polyphase digital filterbank;

FIG. 7 is a graphic representation of the response of the filter shown in FIG. 6;

FIG. 8 is a graphic representation of a band compressed response of the filter shown in FIG. 6.

FIG. 9 is a graphic representation of a first binary encoding;

FIG. 10 is a graphic representation of a second binary encoding;

FIG. 11 is a graphic representation of a third binary encoding;

FIG. 12 is a graphic representation of factors used for word detection;

FIG. 13 is a block diagram of a framed word;

FIG. 14 is a block diagram of an utterance template;

FIG. 15 is a flow chart of a method for generating the utterance template shown in FIG. 14; and

FIG. 16 is a flow diagram of the method used with the apparatus shown in FIG. 1 for extracting features from a speech signal.

DETAILED DESCRIPTION OF THE
INVENTION

An apparatus, generally indicated at 10 in FIG. 1 and embodying the principles of the present invention, includes a means 12 for digitizing an analog speech signal, a means 14 for modulating the digitized speech signal, a means 16 for extracting a spectral envelope, a means 18 for time averaging the extracted spectral envelope and a means 20 for forming an utterance template from the time averaged data.

In the preferred embodiment, a conventional microphone 22 converts a spoken word, or phrase, to an analog signal. The analog signal is inputted to the means 12 wherein the analog signal is digitized. Preferably, the means 12 includes a code/decode analog-to-digital converter that produces, as an output, a string of binary ones and zeros representative of the analog signal inputted thereto. The means 12, preferably includes a band-pass filter having a passband frequency from 0 to 4 kiloHertz as it is within this frequency band that substantially all information is contained in a human voice. The output spectrum 24 of the means 12, in the frequency domain, is shown in FIG. 2. As shown, the signal of interest lies between 0-4 KHz although the sampled output spectrum inherently repeats every 4 KHz. In one specific example, the means 12 is implemented by use of a M7901 device manufactured and marketed by Advanced Micro Devices Corp. of Sunnyvale, Calif.

The means 14 for modulating the digitized speech signal substantially reduces any loss of spectral data due to the finite transition band of the filters within the filterbank. As previously mentioned, due to the quasi-periodic nature of the speech signal, the spectrum of voiced speech exhibits a strong fundamental pitch frequency. If this frequency lies between adjacent bands, i.e., where the finite transition band occurs, substantial spectral data is lost. By smearing the digitized signal, the energy content at that fundamental pitch frequency is expanded and thus becomes discernable by at least one of the adjacent filters.

Preferably, because of the ease of implementation, the modulation is a low frequency square wave, although other forms of modulation can also be used. In one implementation, as shown in FIG. 1, every other group of 128 bits from the means 12 is sign inverted. Specifically, the means 14 includes a first switching means 26 adapted to direct the output from the means 12 either through a first path 28 or a second path 30, the second path 30 being parallel to the first path 28 and including a negator 32 serially located therein. The first switching means 26 is adapted to switch between the first and second paths, 28 and 30 respectively, after every 128 bits are counted by a path counter 34.

The output from the first and second paths, 28 and 30 respectively, is directed into either a first buffer 36 or a second buffer 38 by a second switching means 40. Preferably, the second switching means 40 alternately connects the output from the first and second paths, 28 and 30 respectively, to a different one of the buffers, 36 or 38, after each sixty-four bits, as counted by a buffer counter 42. The buffer counter 42 additionally controls the position of a third switching means 44 that connects, depending on the position thereof, one of the buffers, 36 or 38, to the means 16. As shown, the second and third switching means, 40 and 44 respectively, are arranged such that when bits are being stored in one of the buff-

ers, for example, the first buffer 36, the second buffer 38 is supplying data to the means 16. This control is achieved, in one embodiment, by means of an inverter 45 between the counter 42 and the third switching means 44. Thus, when the output from the counter 42 is a binary value and the switching means, 40 and 44, switch when there is a change in that binary value, the inverter 45 ensures that the switching means, 40 and 44 are opposed.

10 In the present apparatus 10, the means 16 is a polyphase digital filterbank that, unlike conventional filterbanks, effectively divides the input signal thereto into a plurality of bands 46 of equal bandwidth. In the preferred embodiment, thirty-two such bands 46, as shown 15 in FIG. 3, are extracted, each band having a bandwidth of 125 Hz.

Polyphase digital filterbanks, per se, are known in the art, see, for example, DIGITAL FILTERING BY POLYPHASE NETWORK: APPLICATION TO

20 SAMPLE-RATE ALTERATION AND FILTER BANKS; *IEEE Transactions on Acoustics, Speech and Signal Processing*; Vol. ASSP-24, No. 2, April 1976, Pgs. 109-114 by Bellanger et al; DIGITAL PROCESSING

25 TECHNIQUES IN THE 60 CHANNEL TRANS- MUXPLEXER; *IEEE Transactions on Communications*, Vol. Com-26, No. 5, May 1978, Pgs. 698-706, Bonnerot et al; and the article entitled ODD-TIME ODD-FREQUENCY DISCRETE FOURIER

26 TRANSFORM FOR SYMMETRIC REAL-VALUED SERIES; *Proceedings of the IEEE*, March 1976,

30 Pgs. 392-393 by Bonnerot and Bellanger. The above referenced articles are, for the teaching of a polyphase digital filterbank and the use thereof with a Fourier Transform, hereby deemed incorporated herein by reference.

35 Referring now to FIG. 4 a filter 48 in the form of an all pass phase shifting network having a plurality of phase shift elements 50 in parallel is depicted. The input is provided to all of the phase shifters 50 and, as such, no data is rejected, i.e. lost, and there are no significant gain differences between adjacent filters. Thus, a greater dynamic range is achieved since the limitations normally incurred to avoid saturation of a particular filter are removed. This is, in conventional filterbanks 40 the overall dynamic range is restricted to avoid the introduction of excessive gain swings between adjacent bandpass filters. Thus, by eliminating the possibility of such gain variations, the dynamic range of each filter is increased.

50 The filter 48 shown in FIG. 4 effectively generates the basic low pass filter response of FIG. 5. A pair of complex frequency shifted responses as shown in FIG. 5 can be generated by frequency shifting this filter twice. Consequently, in order to effect a thirty-two band filter a total of sixty-four filters must be generated to compensate for the positive and negative frequency shifts. As a result, the filter 48 shown in FIG. 4 must be adapted to effect sixty-four phase shifters.

55 Following the mathematical derivation as set forth in Bellanger et al. the coefficients for the model polyphase digital filterbank 52, as shown in FIG. 6, are derived. Such a model, employing an odd-time odd-frequency Fourier transformer 54, is described in FIG. 6 of the Bonnerot et al. reference.

60 As the theory and derivation of the means 16 is fully described in the above-cited references, further discussion of the intricate details thereof is deemed unnecessary herein. Nevertheless, the primary benefits of a

polyphase digital filterbank are significant in the fields of voice recognition and speaker discrimination. For example, a substantially increased dynamic range, i.e. in excess of 78 dB; a filter of the sixth order and the reduction in real computational steps, i.e. by a factor of thirty-two.

As a consequence, the means 16, in the preferred embodiment, can be implemented, for example, on a TMS320, manufactured and marketed by Texas Instruments of Dallas, Tex., requiring only about 20% of the available computational capacity and time thereof. One preferred program for such an implementation is provided in Appendix A. As a result, the remaining 80% of the computational capacity and time is available for tasks, such as template generation, conventionally delegated to other devices.

The output of the filterbank is a spectral envelope composed of thirty-one bands of odd samples and thirty-two bands of even samples which, after taking the absolute value, via means 60, thereof yields an instantaneous energy estimate for each of the thirty-two frequency bands from 0 to 4 kHz every 4 milliseconds. However, a slower short time average of the spectrum has been found sufficient for voice recognition purposes. Hence, the means 18 for time averaging the extracted spectral data is provided and includes a summing means 56 that sums the odd and even samples of each of the thirty-two bands. The output for the summing means 56 is next divided by two by a conventional divider to provide the short time average.

The output of the divider 58 is inputted to a first order recursive filter 62 to determine the sampled energy of the band. The output of the filter 62, as shown in FIG. 7, is a time smoothed spectral envelope 64 having a frequency resolution of 125 Hz and a time sample spacing of 8 milliseconds.

The voice recognition, the information of interest contained in the spectral envelope lies not so much in the actual spectral energy of the bands but more in the variations thereof in time and frequency. Thus, the means 20 includes a means 66 for band compression, a means 68 for the binary encoding of the differential frequency change between adjacent bands and for binary encoding the energy variation with frequency. The extraction of essential features as performed herein effectively compresses the total information for a speech signal to a relatively fewer number of data to allow efficient storage thereof.

The means 66 for band compression, in the preferred embodiment, reduces the number of bands from thirty-two to sixteen. By conventional digital logic, the effective energy content of the thirty-two bands is combined into the sixteen resultant bands, shown in FIG. 8. In the preferred embodiment, the essential rules for this compression are that the lowest two bands and the four highest bands are discarded since the human voice produces very little energy in these frequency ranges. The third through tenth bands, see FIG. 7, are retained without modification since the energy within this frequency range contains the primary characterization features. The remaining bands, i.e., bands eleven through twenty-eighth, are merged as shown in FIG. 8 since the information content in each band decreases with increasing frequency. As a consequence, the original thirty-two bands of equal bandwidth are reduced to sixteen bands having non-uniform bandwidths.

The means 68 for binary slope encoding is, effectively, a subtractor that outputs a binary value depend-

ing upon the direction of the differential change in energy between adjacent bands. As shown in FIG. 9, the energy bands, although represented as being of equal bandwidth are, in fact, of non-uniform bandwidth as previously discussed and the dotted envelope is represented by the binary numbers indicative of the slope direction between adjacent bands.

Similarly, the sonogram is encoded via a combination averaging device and a subtractor that outputs a binary value depending on whether the energy content of a particular band is greater or less than the mean energy of all sixteen bands. For example, referring to FIG. 10, the mean energy is shown in a dotted horizontal line with the spectrum envelope in an envelope dashed outline. As shown, the binary values for each band are indicative of the relative energy of each band with respect to the mean. If the energy is greater than the mean, a binary one is encoded. If the energy is less, then a binary zero is encoded.

Thus the output of the means 68 for generating a binary slope and encoding the sonogram together is represented by thirty-one bits of information, i.e., fifteen bits of slope data (only fifteen bits are encoded since the differential between the actual bands is being measured) and sixteen bits of sonogram data.

In addition, a summer 72 perceives the total energy contained in the sixteen bands remaining after the band compression to provide two bytes of information representative of the total energy in the compressed bands.

30 The output from the total energy summer 72 and the binary encoding means 68 are inputted to an end point detector 74.

Preferably, the end point detection 74 is a microprocessor based device using generally accepted algorithms and determines the existence of a word based on the following assumptions regarding the spoken word:

1. It is assumed that a spoken word will have an energy level greater than some particular threshold energy. In this instance, the threshold energy, which is an empirically determined value based on a comparison between energy differences during silence and speech, is compared to the two bytes of information previously discussed;

2. The spoken word has a minimum duration below which any data received is considered line noise. In addition, a spoken word is expected to have a maximum duration, in this embodiment, a maximum length of approximately two seconds is assumed.

It is further assumed that there will be no pause during any word greater than about 150 milliseconds. Based on these assumptions, a speech, or utterance, signal 76 can be broken down as shown in FIG. 12. As shown, the actual word, or information of interest, includes a "start" region 78, an "in" region 80, where the word is actually being spoken, and an "end" region 82 where the energy tapers off below a certain predetermined threshold 84.

A flow chart 86 indicating a procedure used in determining the presence or absence of a word from the binary data is shown in FIG. 15. The decision to be made as each group of thirty-one bits of data plus energy information is passed or manipulated by the algorithm is whether or not to deliver that information to a frame buffer 88 such as the one shown in FIG. 13. So long as the conditions for the existence or presence of a word exists, all binary encoded information is stored in the frame buffer 88 that, as shown, is effectively thirty-two bits wide and having the first fifteen bits representa-

tive of the slope information, and the second sixteen bits of information representing being the sonogram data. In addition, the total energy is characterized and determined to be relatively positioned with respect to the overall energy of a particular word. If the energy of a given word is greater than the average energy, a binary bit is encoded in the sixteenth position of the slope string by energy encoding means 90. This provides an additional piece of data in the determination of a subsequently entered utterance template. As shown in FIG. 13, the frame buffer 88 in the preferred embodiment, can contain up to 200 samples of slope, sonogram and energy profile data. That is, if the speech signal represents a long, for example about 2 seconds, word the data storage nevertheless ceases after 200 samples. It has been determined that this is sufficient to identify even a relatively long word.

When the end point of a word is determined, the total frame buffer 88 is further compressed to fit a template 92, i.e. an array, having a predetermined size which, in the preferred embodiment, is effectively a 16×16 bit array containing 256 bits of spectral data. In order to accomplish this, after the data has been entered into the frame buffer 88 it is compressed based on the following rule that eliminates a frame if it is identical to the previous frame providing that there is no elimination of any two consecutive frames. To reduce the data stored in the frame buffer 90 to the preselected number of bits in the template 92, i.e., thirty-two bytes, the number of frames in the buffer 90 is first divided by eight and rounded down to the nearest integer N. Thus, eight composite frames are generated by taking a majority polling of each bit position in each group of N frames. The result is that every template 92 generated consists of 256 bits. The template 92 so generated is passed to a storage medium, not shown in the drawing, for subsequent use in the scoring against an unknown utterance template. One such scoring scheme is fully described in co-pending U.S. patent application Ser. No. 670,521 filed on even date herewith and assigned to the assignee hereof.

The use of the above-described apparatus 10 is en-

hanced by, and incorporates a method for forming or generating utterance templates. Referring to FIG. 16, a flow diagram 94 is shown depicting the steps of the preferred method for generating utterance templates. 5 As shown, the input is first buffered and then spectrally smeared. The spectrally smeared data is then filtered, preferably by a polyphase digital filterbank, and the output thereof is time averaged. Subsequent to the time averaging, the data is compressed, binarily encoded and examined to ascertain the presence or absence of a spoken word. Upon determining the presence of a spoken word, the data is buffered and further compressed whereafter the compressed data is stored in an utterance template having a prespecified and uniform size regardless of the word spoken.

The apparatus and method discussed herein provides numerous advantages unavailable via conventional voice recognition template generating mechanisms. For example, the extracted spectral envelope has a significantly improved filter response as well as an increased overall dynamic range, i.e., 6th order filters are used. In addition, the use of spectral smearing significantly reduces the possibility of losing important information due to the particular pitch frequency of a speaker. Further, the utterance template 92 generated not only is of a prespecified size for all words, but also contains information relating to the total energy of the particular spoken word represented by the template. Yet another advantage, directly resultant from the use of a digital polyphase filterbank, is that the entire utterance template generation can be executed on a single conventional digital signal processor device since, by use of such a filterbank, the mathematical computations required to extract the spectral envelope are significantly reduced.

Although the present invention has been described herein using a specific exemplary embodiment, other configurations or arrangements may also be developed that do not depart from the spirit and scope of the present invention. Consequently, the present invention is deemed limited only by the appended claims and the reasonable interpretation thereof.

What is claimed is:

1. An apparatus for extracting spectral features from a speech signal, said apparatus comprising:

means, including a polyphase digital filterbank, for extracting a spectral envelope of said speech signal, said envelope being composed of a plurality of

spectral envelope segments in frequency bands having uniform bandwidths;
 means for reducing said plurality of spectral envelope segments and bands to a predetermined number of compressed spectral envelope segments and bands having non-uniform bandwidths and each compressed spectral envelope segment having an energy level;
 means for representing features of said compressed spectral envelope segments in said compressed bands by a first and a second set of binary values, said first set of binary values being representative of the variations between the energy level of each compressed spectral envelope segment and the energy level of an adjacent compressed spectral envelope segment, and said second set of binary values being representative of the relative energy levels of said compressed spectral envelope segments; and
 means for storing said first and second sets of binary values.

2. Apparatus as claimed in claim 1, further comprising:
 means for filtering and digitizing said speech signal and providing said filtered and digitized signal to said means for extracting a spectral envelope, said filtering means having a pass band at least including primary frequencies of the human voice.

3. Apparatus as claimed in claim 1, further comprising:
 means for spectrally smearing said speech signal and thereafter providing said speech signal to said means for extracting a spectral envelope.

4. Apparatus as claimed in claim 3 wherein said spectral smearing means comprises:
 means for impressing a square wave modulation on said speech signal.

5. Apparatus as claimed in claim 4 wherein said means for impressing a square wave modulation on said speech signal includes:
 an input for receiving said speech signal;
 a first path and a second path, said first and said second path being in parallel with each other;
 a negator, said negator being serially included in said second path;
 means connected to said input for periodically switching said speech signal between said first and said second paths; and
 an output connected to said first and second paths for providing the square wave modulated speech signal.

6. Apparatus as claimed in claim 1, further comprising:
 means for sampling said speech signal on a periodic basis and for providing signal samples to said means for extracting whereby said feature representing means generates one said first set and one said second set of binary values for each signal sample.

7. Apparatus as claimed in claim 6, further comprising:
 means for representing the total energy of said compressed spectral envelope segments as a binary value.

8. Apparatus as claimed in claim 7 wherein said storing means stores, for each signal sample, said first set, said second set and said binary value representing the total energy of said signal sample as a frame.

9. An apparatus as claimed in claim 8, wherein said storing means stores a plurality of frames, said plurality of frames representing a speech signal, said apparatus further comprising:
 means for programmably compressing the frames in said storing means to a predetermined number of frames and outputting said predetermined number of frames as a template representing said speech signal.

10. An apparatus as claimed in claim 1, wherein said polyphase digital filterbank comprises a polyphase network and an odd-time odd-frequency Fourier transformer.

11. An apparatus as described in claim 10, wherein said Fourier transformer provides 32 bands of odd samples and 32 bands of even samples, said apparatus additionally comprising:
 means for providing the absolute value of each said sample; and
 means for time averaging said odd and even samples from said means for providing absolute values.

12. An apparatus as described in claim 11, wherein said time averaging means comprises:
 means for summing said odd and even samples of each band; and
 means for dividing said sums by 2, whereby a single value is provided for each of said 32 bands.

13. A method for extracting spectral features from a speech signal, said method comprises the steps of:
 extracting a spectral envelope from said speech signal by filtering said speech signal with a polyphase digital filterbank, said envelope being composed of a plurality of spectral envelope segments in frequency bands having uniform bandwidths;
 reducing said plurality of spectral envelope segments and bands to a predetermined number of compressed segments and bands having non-uniform bandwidths and each compressed segment having an energy level;
 binarily encoding features of said compressed segments into a first and a second set of binary values representing the variations between the energy level of each compressed segment and the energy level of the next higher compressed segment as said first set, and representing relative energy levels of said segments as said second set; and
 storing said first and second sets of binary values.

14. Method as claimed in claim 13, further comprising the steps of:
 filtering and digitizing said speech signal prior to extracting said spectral envelope, said filtering passing the primary frequencies of the human voice.

15. Method as claimed in claim 13 further comprises the step of:
 spectrally smearing said speech signal before extracting said spectral envelope.

16. Method as claimed in claim 15 wherein said spectral smearing step comprises:
 impressing a square wave modulation on said speech signal.

17. Method as claimed in claim 16 wherein the step of impressing a square wave modulation on said speech signal comprises the steps of:
 providing first and second paths in parallel with each other, said second path including a negator; and

periodically switching said speech signal between said first and second paths, whereby a square wave modulation is impressed on said speech signal.

18. Method as claimed in claim 13, further comprises the step of:

sampling said speech signal on a periodic basis prior to extracting said spectral envelope whereby said binary encoding step generates one said first set and one said second set of binary values for each signal sample.

19. Method as claimed in claim 18, further comprising the steps of:

representing the total energy of said compressed segments as a binary value.

20. Method as claimed in claim 19 wherein said storing step includes storing, for each signal sample, said first set, said second set and said binary value representing the total energy of said signal sample as a frame.

21. A method as claimed in claim 20, additionally comprising the steps of:

storing a plurality of frames, said plurality of frames representing a speech signal;
programmably compressing the stored frames to a predetermined number of frames; and
outputting said predetermined number of frames as a template representing said speech signal.

22. A method as described in claim 13, wherein said step of extracting a spectral envelope provides 32 bands of odd samples and 32 bands of even samples, said method additionally comprising the steps of:

providing the absolute value of each said sample; and
time averaging the absolute values of said odd and even samples to provide a single output of each of said 32 bands.

23. A method as described in claim 22, wherein said step of time averaging comprises the steps of:
summing said odd and even samples of each band;
and dividing said sums by 2.
